UNITED STATES PATENT OFFICE.

ELMER L. MATER, OF DOWAGIAC, MICHIGAN.

SAFETY DEVICE FOR ELEVATORS.

SPECIFICATION forming part of Letters Patent No. 784,410, dated March 7, 1905.

Application filed November 21, 1904. Serial No. 233,717.

To all whom it may concern:

Be it known that I, ELMER L. MATER, a citizen of the United States, residing at Dowagiac, in the county of Cass and State of Michigan, 5 have invented new and useful Improvements in Safety Devices for Elevators, of which the following is a specification.

This invention relates to safety devices for elevators.

10 The objects of the invention are to improve and simplify the construction of such devices; furthermore, to increase their efficiency in operation.

With the foregoing and other minor objects in view, which will appear as the description proceeds, the invention resides in the combination and arrangement of parts and in the details of construction hereinafter described and claimed.

15 In the accompanying drawings, forming part of this specification, Figure 1 is a side elevation of an elevator equipped with the improvements of the present invention. Fig. 2 is a plan view of the eccentric levers and supporting means therefor.

Like reference-numerals indicate corresponding parts in the different views.

Referring to the drawings, the reference-numerals 1 and 2 indicate tracks, such as are 20 usually employed in connection with elevator-shafts, and 3 indicates an elevator, which may be of any suitable form and construction. Attached to the upper portion of the elevator 3 is a plate, such as 4, to which are secured up-

wardly-inclined supporting-arms 5, arranged, preferably, in pairs. Pivotedly mounted between the outer ends of each pair of supporting-arms 5 is a lever, such as 6, having an eccentric outer end 7 and an elongated inner 25 end 8. Attached to the inner ends of the levers 5 is an elevator-rope or flexible element 9. Located beneath the inner ends of the levers 6 is an ordinary form of electromagnet 10, which is connected, by means of the wires 11, with the arms 5. The tracks 1 and 2 are 30 in electrical circuit by means of wires 12 with any suitable form of battery 13.

Constructed as above described the operation of the improved device is as follows: As 35 soon as the rope or flexible element 9 breaks

the inner ends 8 of the levers 6 descend, thus throwing the eccentric portions 7 of said levers into frictional contact with the tracks 1 and 2. The momentum of the elevator causes said eccentric ends of the levers to become 55 securely jammed against the tracks, thus stopping the elevator. Furthermore, the moment that the eccentric portions 7 of the levers contact with the tracks 1 and 2 an electrical circuit is formed through the wires 12, tracks 1 and 2, eccentric portions 7, supporting-arms 5, and electromagnet 10, the function of said circuit being to energize the magnet 10 and cause it to attract the inner ends of the levers 8, thus causing an increase in the jamming 60 action of the eccentric portions 7 against the tracks 1 and 2. It will be apparent, therefore, that three important forces combine to increase the efficiency of the improved device of this invention in arresting the accidental 65 descent of an elevator—first, the tendency of the elongated inner ends of the levers 6 to descend by gravity and throw the shoes or eccentric portions 7 against the tracks 1 and 2; second, the momentum of the car, which 70 as soon as the shoes or eccentric portions 7 contact with the track causes them to become jammed, and, third, the action of the magnet 10.

Changes in the precise embodiment of invention illustrated and described may be made within the scope of the following claims without departing from the spirit of the invention or sacrificing any of its advantages.

Having thus described the invention, what 80 is claimed is—

1. The combination with an elevator and a track therefor, of a lever on said elevator adapted to contact with said track, a flexible element connected with said lever for hoisting the elevator and maintaining said lever normally out of contact with said track, and an electromagnet adapted to attract said lever as soon as it moves into contact with said track. 95

2. The combination with an elevator and a track therefor, of supporting-arms on said elevator, levers pivoted on said supporting-arms and having eccentric outer portions and elongated inner portions, a flexible element 100

connected with the elongated inner portions of said levers for hoisting the elevator and maintaining the eccentric portions of said levers out of contact with said track, an electro-
5 magnet adapted when energized to attract the elongated inner ends of said levers, electrical connections between said electromagnet and eccentric portions of said levers, and a battery in circuit with said track, whereby, when
10 the flexible element breaks the elongated ends

of the levers descend by gravity and throw the eccentric portions thereof into contact with the track.

In testimony whereof I affix my signature in presence of two witnesses.

ELMER L. MATER.
